MOUNTING FOR SLIDING DOOR FRAMES

William T. Hormes, Catonsville, Md.

Application August 25, 1944, Serial No. 551,167

8 Claims. (Cl. 312—189)

1

This invention pertains to store-furniture cabinet unit containers of the type in which slidingly mounted glass doors are arranged to close the front of a unit. Such a unit container is illustrated and described in a pending application filed August 20, 1942, Serial No. 455,481 which has become Patent No. 2,367,124, dated Jan. 9, 1945, to which reference is made for purposes of illustration only.

One of the objects of the invention is to provide simple and effective means for releasably mounting a door-supporting frame within a store-furniture unit container which is to be equipped with sliding doors. A further object is to provide a door-frame mounting of the character mentioned by means of which the frame may be vertically adjusted within said unit, after the frame and its mounting have been installed. A further object is to provide a door-frame mounting of the character mentioned by means of which the position of the frame may be so adjusted as to bring its front face in alignment with the front edges of the end walls of the cabinet unit container. Another object is to provide a door-frame mounting which may be quickly installed or removed at will, with a minimum expenditure of time and labor.

The invention will be hereinafter fully set forth and particularly pointed out in the claims.

In the accompanying drawings:

Fig. 1 is a diagrammatic front elevation illustrating a store-furniture cabinet unit container equipped with slidingly mounted doors.

Fig. 2 is a horizontal sectional view on line 2—2, Fig. 1.

Fig. 3 is an enlarged horizontal sectional view, with parts broken away, illustrating the door-frame mounting of the present invention in top plan view.

Fig. 4 is a fragmentary elevation of a store furniture unit with the door frame mounting in supported position.

Fig. 5 is an enlarged detail view illustrating the means for effecting adjustment of the door frame.

Fig. 6 is a detail sectional view illustrating one means for anchoring the frame mounting to an end wall of the cabinet unit container.

Referring to the drawing C designates a store-furniture cabinet unit container which may be of any desired or well known construction. A store furniture cabinet C of the character disclosed and claimed in a co-pending application Serial No. 455,481, has been selected for purposes of illustration and without intent to limit the invention in this particular. As shown in the pres-

2

ent drawing, the cabinet C is provided with a base 10, a top 11, two ends 12, and a back 13, all assembled to provide a complete cabinet structure open at the front. Unit container inserts are preferably removably positioned within the cabinet C, and are normally retained therein by molding strips M removably attached to the front edges of the end walls 12, in a manner not shown in detail in the present drawing, but fully shown and described in the above identified application, to which reference is hereby made. The end walls 12 are provided with vertical channels 14 in which are located slotted strips 15 for receiving removable lugs to support shelving. These strips and lugs may be of any desired construction, but it is preferred to employ the arrangement illustrated in a copending application filed August 20, 1942, Serial No. 458,480.

Two doors D are mounted in overlapped sliding relation within a door-carrying frame F which is positioned adjacent the front of the cabinet C. Said frame is constructed with two parallel channels 16, 16a, one for each door, and arranged to provide a rectangular structure of proper dimensions to be inserted into the front of the cabinet. The frame F is adjustably mounted within the cabinet by mountings A which are connected to opposite vertical sides of the frame.

Each frame mounting A consists of a supporting plate 20 which is provided at one end with oppositely disposed ears 21, having screw threaded openings 22 therein, said ears being joined to the edges of the plate by reinforcing flanges 23. The lower edge of said plate contiguous to the other end thereof is provided with a plurality of horizontally spaced notches 24, positioned to selectively register with a slotted strip 15, and to be engaged by a lug 25, which may be selectively and releasably engaged with any of the slots in said strip. Fixedly attached to opposite sides of the frame F and to the inner surfaces thereof, are frame-carrier members 27, each provided with oppositely disposed ears 28, having openings 29 which are positioned to register with the openings 22 of the plate 20. Rotatively mounted in the openings 29 are the reduced ends 30 of a screw threaded rod 31, the threads of which engage the threads of said openings 22. The reduced ends 30 of said rod 31 provide the latter with end shoulders which engage the inner surfaces of the opposite ears 28, so that said rod is held against longitudinal movement although free to rotate. The upper end of the rod 30 is provided with means by which it may be engaged by a suitable tool to effect rotation thereof. For

purposes of illustration and without intending to limit the invention, a slot 32, to be engaged by a screw driver is shown for this purpose.

In practice, the plate 20, frame-carrier member 27 and the screw 31 are assembled in the relation shown in the drawing, and the frame-carrier member of each mounting A is spot welded or otherwise attached to a side of the frame F, in the manner hereinabove described. When it is desired to install a door frame F, lugs 25 are engaged with the strips 15 at the approximate horizontal plane to be occupied by the lower edge of the plate 20. As the frame F is inserted into the front opening of the cabinet C, one of the notches 24 of each plate 20 is engaged with its lug 25. In this manner each plate 20 is removably anchored to its end wall 12, and the two plates will sustain the weight of the frame at the opposite ends of the latter. After the frame mounting is so installed relative pivotal movement of the frame-carrier 27 and the supporting plate 20 is prevented. In this connection, it is to be understood that the lug 25 will be engaged with a selected notch 24 which will place the frame F in such a position that its front face will be in alignment with the front outer edge of the adjacent end wall 12. Then by rotating the shaft 31, the reaction member 27 will be caused to travel upwardly or downwardly, according to the direction of rotation of the rod 31, so as to correspondingly adjust the frame F to its required juxtaposition with respect to the under face of the top 11 of the cabinet C. It is contemplated that molding M will be removably attached to the front edges of the end walls 12 of the cabinet unit container, and so positioned as to overlap the ends of the frame F after its final positioning in the manner illustrated in a pending application Serial Number 455,481.

The advantages of the invention will be readily understood by those skilled in the art to which it belongs. For instance, it will be observed that a very simple and inexpensive door-frame mounting is provided for a store furniture unit, which mounting is capable of firmly supporting said frame in its operative position. An important advantage is that accurate location of the door frame with respect to the cabinet opening is assured, because of the possibility of readily adjusting the position thereof after its initial installation. Another advantage is that the mounting is so constructed and arranged that it permits of quick installation of the door frame, or ready removal thereof, as occasion may require.

It is to be understood that although only two frame mountings A have been shown and described, the invention is not limited in this particular, because any desired number may be used, depending upon the size of the door frame to be installed.

Having thus explained the nature of the invention and described an operative manner of constructing and using the same, although without attempting to set forth all of the forms in which it may be made, or all of the forms of its use, what is claimed is:

1. A sliding-door-frame mounting of the character described having in combination a supporting plate provided at one end with means for adjustably engaging an anchoring member located within a store furniture unit, said plate having spaced-apart ears at its other end provided with screw threaded openings therein, a frame-carrier member adapted to be secured to a side of the door frame to be supported, said

frame-carrier member also having ears provided with openings in register with the openings of the ears of said plate, and a threaded rod rotatively mounted in the ears of said frame-carrier member, said rod having means engaging said last mentioned ears to prevent axial movement thereof, said rod having threaded engagement with the threads of the openings in the ears of said plate.

10 2. A sliding-door-frame mounting of the character described having in combination a supporting plate provided at one end with means for adjustably engaging an anchoring member located within a store furniture unit, said plate having spaced-apart ears at its other end provided with screw threaded openings therein, a frame-carrier member adapted to be secured to a side of the door frame to be supported, said frame-carrier member also having ears provided with openings in register with the openings of the ears of said plate, a threaded rod extended through and having threaded engagement with the threaded portions of the openings in the ears of said plate, said rod having reduced ends extended through and 15 rotatively mounted in the openings in the ears of the frame-carrier member, said rod having portions engaging the ears of said frame-carrier member so that said rod is free to rotate between the ears of the frame-carrier member but is held 20 against axial movement with respect to said ears.

25 3. A sliding-door-frame mounting of the character described having in combination a supporting plate provided at one end with means for adjustably engaging an anchoring member located 30 within a store furniture unit, said supporting plate at its other end being provided with ears having threaded openings therein, a frame-carrier member adapted to be secured to a side of the door frame to be supported, said frame-carrier member being also provided with ears having openings therein, the last mentioned openings being in alignment with the threaded openings of the ears of said supporting plate, a screw-threaded rod rotatively mounted in the ears of said 35 frame-carrier member and having threaded engagement with the threaded openings in the ears of said supporting plate, and means for preventing longitudinal movement of said threaded rod with respect to said frame-carrier member.

40 4. The combination with a store furniture cabinet having its end walls provided with vertically disposed slotted strips, and a door frame located within said end walls, of a frame carrier member attached to each side of said frame, a threaded rod rotatively mounted in said frame carrier member, said frame carrier member and said threaded rod having complementary means for holding said rod against axial movement, a supporting plate provided at one end with internally threaded openings having threaded engagement with each of said rods, each plate having notches in its lower side near the other end thereof extended across an adjacent slotted strip, and lugs removably mounted in the slotted strips and received in notches of said plates.

45 5. A sliding door frame support of the character described having in combination supporting plates adapted to be mounted on oppositely disposed walls of a store furniture unit and in parallel relationship, door frame carrier members adapted to be secured to the door frame to be supported, elements disposed vertically in said door frame carrier members and connected thereto by means whereby said elements are rotatable but not slid able, and cooperating means

on said elements and said supporting plates so constructed and arranged that rotation of said elements will move said supporting plates in vertical directions.

6. A sliding door frame support of the character described having in combination supporting plates adapted to be mounted on oppositely disposed vertical walls of a store furniture unit and in parallel relationship, each of said supporting plates having means whereby it may be supported for adjustment in a horizontal plane, door frame carrier members adapted to be secured to the door frame to be supported, shafts disposed vertically in said door frame carrier members and connected thereto by means whereby said shafts are rotatable but not slidable, threads on said shafts, and portions of said supporting plates threadedly engaged with the threads of said shafts, whereby rotative movement of said shafts will move said supporting plates in vertical direction.

7. In a store furniture cabinet having side walls, a door frame within said cabinet, cooperating means on said frame and said side walls for supporting said frame on said walls, said cooperating means comprising means whereby said frame may be adjusted laterally of said side walls, and means whereby said frame may be adjusted longitudinally of said side walls.

8. In a store furniture cabinet open at its front and having side walls, a door frame mounted in vertical position in said front opening by means comprising anchoring members on said side walls, plates carried by said door frame having means whereby they are supported by engagement with said anchoring members, means on said plates whereby the latter may be adjusted in horizontal direction upon said anchoring members, and means for effecting vertical adjustment of said frame upon said plates.
